UNITED STATES PATENT OFFICE.

PETER WELIN, OF WORCESTER, MASSACHUSETTS, ASSIGNEE, BY MESNE ASSIGNMENTS,
TO LAWRENCE MAXWELL, OF CINCINNATI, OHIO.

DOUBLE-SCALE TRACKER.

1,123,049.

Specification of Letters Patent. Patented Dec. 29, 1914.

Application filed September 5, 1908. Serial No. 451,803.

To all whom it may concern:

Be it known that I, PETER WELIN, a citizen of the United States, residing at Worcester, in the county of Worcester and State of Massachusetts, have invented a new and useful Double-Scale Tracker, of which the following is a specification.

This invention relates to that class of mechanical musical instruments in which the 10 operation of the same is controlled by a traveling music-sheet.

More specifically it relates to that type of said instruments in which music sheets having different ranges are desired to be employed. At present there are music sheets 15 having a range of eighty-eight notes, and the ordinary sheets having a range of sixty-five notes.

The principal objects of this invention 20 are to provide a simple and convenient construction of tracker on which both kinds of music sheets can be employed without necessitating any complicated manipulation of the parts to make the change; and to provide 25 a construction in which there will be no leakage on account of the movable elements necessary to make the change from one scale to the other.

Another feature of the invention is the 30 form of the tracker itself or the front plate thereof, which is so shaped that although it has a double line of note channels, yet the surface over which the paper moves will not be materially increased over the surface ordinarily present in single scale trackers.

The invention also involves certain improvements in features of construction and combinations of parts as will appear hereinafter.

Reference is to be had to the accompanying drawings, in which—

Figure 1 is a front elevation of a tracker-box showing one form in which this invention may be applied thereto; Fig. 2 is a 45 similar view of a portion of the tracker on an enlarged scale. Fig. 3 is a central transverse sectional view of the same; Fig. 4 is a plan of the connecting plates used for the air tubes, and Fig. 5 is a sectional view of 50 the same.

The invention is shown as applied to a tracker-box 10 having the usual music and take-up rolls 11 and 12. As usual the main portions of this box are constructed rigidly 55 and the boards or plates 13 at the back come

together near the center to hold a stationary member 14 constituting a part of the tracker. This stationary member is provided with two longitudinal sets of perforations 15 and 16. In one of these sets there are 60 preferably sixty-five perforations, and in the other eighty-eight. The sixty-five perforations are preferably arranged in two rows as is well understood in practice, being staggered so that they can be contained in 65 a longitudinal space substantially equal to the length of the corresponding row of channels in the tracker. The perforations 15 are shown as being arranged in three rows, because in each set there are a larger 70 number of channels and they occupy a smaller space. The several perforations at the back of the member 14 are connected by means of lead or other tubes 17 with a pair 75 of channel plates 18. These two plates together are provided with perforations equal to the number of lead pipes entering them, and consequently to the number of perforations 15 and 16 combined. Below each plate 18 is another plate 19 having a smaller 80 number of perforations 190. The number of perforations in the two plates 19 is equal to the number in the larger set of perforations in the tracker, in this case eighty-eight. Some of the perforations 190 communicate 85 with two perforations 20 in the upper plate, and others communicate with only one. It will readily be understood that the connections may be so arranged that each perforation 16 of the smaller series can 90 be connected by its lead pipe 17 with a perforation 20 corresponding with the perforation 15 of the other series controlling the same note, and consequently there will be only one series of pipes 21 or other connections 95 from the perforations 19 to the action.

For communicating with the perforations 15 and 16 the tracker is provided with an outer or front movable member 22. This member is provided with two series of channels 23 and 24 corresponding respectively to the perforations 15 and 16. The channels in each series at the front of the movable member are located in longitudinal alignment, but the member or plate 22 is perforated in such a manner that these channels when they extend through the rear thereof are located in the same relative position in each series as the perforations 15 and 16, but the rear ends of the channels of the series 100 105 110

23 are offset slightly from the rear ends of the channels of the series 24, so that when the plate or member 22 is moved to such position along the stationary member 14 that the channels 23 register with the perforations 15, all of the channels 24 will be out of registration with the perforations 16, and when the plate is slid along so as to bring the channels 24 into registration with the perforations 16 the channels 23 will be out of registration with the perforations 15, and consequently will be closed.

10 In addition to the regular note channels in the series 23 and 24, each one is preferably provided with two or more additional accenting or modulating channels 25 at the ends, these preferably being located with their forward ends slightly in advance of the forward edges of the note channels of that 20 row.

15 The front plate 22 is provided with a series of countersunk slots 26 having shoulders 27 at the bottom of the counter-sinks. Each slot is preferably arranged longitudinally, and from the front of the stationary member project a series of headed studs or screws 28 having springs 29 thereon bearing between the under sides of the heads and the fronts of said shoulders. These slots 30 are counter-sunk to such a depth that the studs are substantially contained within them. As the plate slides, the springs 29, through washers 30 bear on the shoulders 27. This holds the plate firmly against the 35 stationary member.

25 In order to provide against leakage a sheet 31 of flexible material, preferably of rubber, is located between the two members 14 and 22, and fixed to one of them, preferably the stationary one. This sheet is provided with perforations registering with the perforations of the member to which it is attached, and on account of the nature of the material, it permits the sliding motion 40 to take place and at the same time prevents a leakage.

30 It will be observed that the front plate or member 22 is provided with a longitudinal groove 32 on the front thereof midway between the two series of channels. This is provided for two purposes, first, to reduce the surface along which the note sheet must come into contact with the tracker, thus permitting it to be moved along the same more 35 readily than would be the case if the sheet were held against the larger surface. This is desirable in the present case on account of the two rows of tracker channels which necessarily increase the width of the tracker. 40 The other object of this channel is to permit the studs to be contained within the tracker and yet be accessible from the front without bringing them into such position that they can come into contact with the note sheet. It will be understood, of course,

that the movable member 22 is held in position solely by the spring tension caused by the studs, and is guided thereby.

5 The movable member of the tracker is shown as provided with a scale 33 fixed thereon having marks and indicating characters thereon to represent the two scales. A stationary pointer 34 is mounted on the stationary part of the tracker-box and projects into such position that it will indicate 70 on the scale which kind of a note sheet is to be employed with the tracker in that position.

10 The sides of the tracker-box are provided with recesses 35 and the ends of the movable member of the tracker project into the same in all positions thereof, so that no matter where the tracker is adjusted there will be 80 no visible space between the end of the tracker and the edge of the tracker-box.

15 In order to provide for moving the tracker, one end of the same has a projecting arm 36 extending through the end of the tracker box, and to this is connected a lever 37 which is pivotally supported at one end 90 by a stud 38 on the outside of the box, and which is connected with a screw 39 at the other end which passes through a fixed nut 40 in the side of the tracker. The screw is threaded into a rod 41 pivotally connected 95 with the lever, and the screw is also provided with a head 42 on the inside of the box. On account of the slow motion imparted by the screw, the plate 22 can be moved readily in spite of the opposition due to the 100 spring pressed studs.

20 One of the recesses 35 in the side of the tracker extends clear through the same, and it is through this that the tracker plate 22 is introduced when the machine is set up.

25 While I have shown and described a preferred embodiment of the invention, I am aware that many modifications may be made therein by any person skilled in the art without departing from the scope of the invention as expressed in the claims. Therefore I do not wish to be limited to all the 110 details shown and described, but

30 What I do claim is:—

1. A tracker for a mechanical musical instrument comprising a stationary member having two sets of channels therethrough, one having eighty-eight channels and the other sixty-five, the eighty-eight channels being arranged in three longitudinal rows 115 and the sixty-five channels in two rows, and a sliding plate having two rows of openings on the front side and two sets of openings on the rear each communicating through the plate with one of those on the front, said 120 rear openings of each set being located in the same relative positions as the channels in the corresponding set of the stationary member, but those of the two sets as a whole being so located with respect to each other 125 130

that both sets of those of the sliding plate will not register at the same time with both sets of channels in the stationary member.

2. A tracker for a mechanical musical instrument comprising a stationary member having two sets of channels therethrough, and a sliding member slidably mounted on the front of the stationary member, and having two rows of channels adapted to register respectively with the first mentioned sets of channels, and yielding means for holding said sliding member in close contact with the stationary member comprising headed studs projecting from the front of the stationary member said sliding member having counter-sunk slots for receiving the studs and springs bearing on the heads of the studs and on the shoulders of the countersunk slots.

3. A tracker for a musical instrument comprising a member having two sets of channels a longitudinally sliding front plate having two rows of channels therein adapted to register respectively with the first mentioned sets of channels, a longitudinal groove between said rows, and means in said groove for holding said plate in position.

4. A tracker for a musical instrument comprising a member having two sets of channels a longitudinally sliding front plate having a plurality of sets of channels therein adapted to register respectively with the first mentioned sets of channels, a scale on said plate, a stationary pointer extending to the scale, and means for sliding said plate.

5. The combination with a tracker box, and a stationary member provided with channels, said tracker box having two opposite recesses in its ends, of a channelled tracker plate movable along the front of said member, and projecting at its ends into both of said recesses in all its positions, and means mounted on the tracker box for sliding said plate.

6. The combination with a tracker box and a tracker member provided with channels, said tracker box having two opposite recesses in its ends, one of them extending clear through the end, of a tracker plate movable along the front of said tracker member and projecting at its ends into both of said recesses in all its positions, whereby it can be adjusted back and forth without disclosing its end from the front and whereby it can be inserted in place from the end.

7. A tracker for a musical instrument comprising a stationary member having two sets of channels, a longitudinally sliding front plate having two sets of channels therein adapted to register respectively with the first mentioned sets of channels in different positions of the sliding plate, means for sliding said plate longitudinally on the stationary member to bring either of its sets of channels into communication with one of the sets of channels in said member, and means for guiding the sliding front plate to move in a true longitudinal direction.

8. A tracker for a mechanical musical instrument comprising a stationary member having two sets of channels therethrough, a sliding member slidably mounted on the front of the stationary member and having two rows of channels adapted to register respectively with the first mentioned sets of channels in different positions of the sliding member, and means for holding said sliding member in close contact with the stationary member comprising headed studs projecting from the front of the stationary member, said sliding member having counter-sunk slots for receiving the heads of said studs.

In testimony whereof I have hereunto set my hand, in the presence of two subscribing witnesses.

PETER WELIN.
